CLAIM

The ornamental design for a footwear outsole, as shown and described.

DESCRIPTION

FIG. 1 is a bottom perspective view of a footwear outsole in accordance with a first embodiment of the ornamental design; FIG. 2 is a left side elevational view of the footwear outsole thereof; FIG. 3 is a right side elevational view of the footwear outsole thereof; FIG. 4 is a bottom plan view of the footwear outsole thereof; FIG. 5 is a bottom perspective view of a footwear outsole in accordance with a second embodiment of the ornamental design; FIG. 6 is a left side elevational view of the footwear outsole thereof; FIG. 7 is a right side elevational view of the footwear outsole thereof; and, FIG. 8 is a bottom plan view of the footwear outsole thereof. Broken lines are environmental only and form no part of the claimed design. Broken lines adjacent shaded areas of the design represent the bounds of the claimed design and are not themselves a part of the claimed design.

1 Claim, 8 Drawing Sheets
